UNITED STATES PATENT OFFICE.

HENRY M. LOOMIS, OF CLAVERACK, NEW YORK.

HUSKING-ROLL FOR CORN-HUSKING MACHINES.

1,059,676.

Specification of Letters Patent. Patented Apr. 22, 1913.

Application filed January 10, 1913. Serial No. 741,283.

To all whom it may concern:

Be it known that I, HENRY M. LOOMIS, a citizen of the United States, residing at Claverack, in the county of Columbia and 5 State of New York, have invented certain new and useful Improvements in Husking-Rolls for Corn-Husking Machines; and I do hereby declare the following to be a full, 10 clear, and exact description of the same, reference being had to the accompanying drawings, forming part of this specification, and to the figures and letters of reference 15 marked thereon.

This invention relates to improvements in 20 corn husking rolls for husking machines of the type illustrated in Patent No. 705,770, July 29, 1902, and it has for its object to provide rolls which shall completely remove the husks from the ears, and which are rigid 25 and strong and capable of withstanding rough usage.

To these ends the invention consists in certain novel details of construction and combinations and arrangement of parts all 25 as will be now described and the particular features of novelty pointed out in the appended claim.

Referring to the accompanying drawings, 30 wherein is illustrated the preferred form of the invention,—Figure 1 is a perspective view of roller constructed in accordance with the present invention; Fig. 2 is a section through two of the coöperating rolls.

Similar letters of reference in the several 35 figures indicate the same parts.

The letter A indicates one of the rollers, preferably made of hard wood in solid halves and mounted on metal cores or shafts 40 *a*, Fig. 2, the halves being clamped in position by bolts B, shown in dotted lines. The rolls are arranged in pairs, as shown in Fig. 2, and the number of pairs employed is immaterial.

Embedded in the rolls and secured in 45 place by means of screws or other suitable fastening means C, are a series of longitudinal channel bars or strips D, substantially U-shaped in cross section, the flat surface of 50 the strips being flush with the periphery of the rolls, forming longitudinal flat surfaces which are so arranged that the surface on

one roller will coöperate with the flat surfaces on the companion roller.

Projecting beyond the face of one of the strips D, are a series of husking pins E, 55 arranged longitudinally of the strip, which are adapted to enter a recess or groove in the coöperating roll. In the present instance this recess or groove is formed by a U-shaped channel bar or strip F, similar to 60 the strip D, but inverted, and let into the periphery of the roller with the side flanges substantially flush with the periphery of the roll. The strips F are secured to the roll by means of screws G or other suitable fastening means, hoops or bands H, being also applied to the ends of the rollers encircling 65 the ends of all of the strips.

The rollers as before mentioned are arranged in pairs, and are run at the same 70 speed so that the pins on one roller will enter the groove on the coöperating roller.

From the above description it will be seen 75 that the roll is strong and rigid and easily manufactured.

By having the flat metal coöperating surfaces the shucks on the ears are allowed to drop below the periphery of the roller so that the husking pins may more easily grasp the husks and carry them down between the 80 rollers thereby tearing the husks from the ears.

Having thus described my invention, what I claim as new and desire to secure by Letters Patent of the United States, is— 85

A husking roll for corn husking machines, having flattened surfaces on its periphery extending from end to end of the roll formed by U-shaped metal strips embedded in the roll with the flat surface of the strip 90 flush with the periphery of the roll, husking pins projecting beyond the face of one of the strips, and a U-shaped metal strip embedded in the roll and extending the length thereof, the outer edges of the flanges of the strip being flush with the periphery of the roll whereby a longitudinal groove in the 95 face of the roll is formed.

HENRY M. LOOMIS.
